UNITED STATES PATENT OFFICE.

JAMES S. PURSLEY, OF ATLANTA, GEORGIA.

TIRE-TIGHTENER.

SPECIFICATION forming part of Letters Patent No. 288,954, dated November 20, 1883.

Application filed March 29, 1883. (No model.)

To all whom it may concern:

Be it known that I, JAMES S. PURSLEY, of Atlanta, in the county of Fulton, and in the State of Georgia, have invented certain new and useful Improvements in Tire-Tighteners; and I do hereby declare that the following is a full, clear, and exact description thereof, reference being had to the accompanying drawings, and to the letters of reference marked thereon, making a part of this specification.

This invention relates to certain improvements in tire tighteners; and it has for its objects to provide a device that may be readily applied to a wheel and employed to force the felly away from the shoulder on any particular spoke or spokes, or the whole series of spokes successively, to make room for the insertion of a washer, whereby the felly and tire may be set closely and securely together, as more fully hereinafter specified. These objects I attain by the means illustrated in the accompanying drawings, in which—

Figure 1 represents a perspective view of my improved device, and Fig. 2 a vertical sectional view thereof.

The letter A indicates a recessed metallic head, in which is adapted to slide a metallic bar, B, which, at its outer end, is provided with bifurcated lateral extensions D, for the purpose hereinafter specified. The said bar, on one side, is provided with a series of cog-teeth, E, with which intermesh the cogged portion of the lever F, fulcrumed to a pin, G, passing through the jaws of the head, for the purpose hereinafter specified. The said bar is provided also with a series of ratchet-teeth, H, with which is adapted to engage a pawl, I, to hold the bar against backward movement. The outside of the head is provided with lugs K, between which are pivoted the wings or plates L, which are slightly curved, so as to embrace any particular spoke, one of said wings being provided with lugs M, between which is pivoted a lever, N, the other wing being provided with similar lugs, between which the lever may be set, so as to clamp the wings to the spoke, the lever being provided with a screw-thread, P, and binding-lever R, whereby the wings may be tightened upon the spoke. The head, at each side, is provided with lugs S, through which pass the ends of a bent rod, T, which forms a frame, the free end of which is adapted to rest upon the hub, the frame being adjusted and held in proper

position by means of the set-screws U, as shown in Fig. 1 of the drawings. The letter V indicates a spring, by which the pawl I is held in a normal position.

The operation of my invention is as follows: The operating-lever is brought to a position at right angles to the head, forcing the metallic bar fully into the same. The bifurcated portion of said bar is then placed around the spoke and brought to bear directly upon the inner part of the felly. The jaws L are then clamped around the spoke. The bent metallic rod is then adjusted so that its free end will set against the hub, and is confined in such position by tightening up the set-screws. The operating-lever is then borne upon, so as to force it to the position shown in the drawings, or approximately thereto, forcing the bifurcated extensions of the sliding bar against the inside of the felly and pushing the same away from the shoulder at the end of the spoke, so as to permit the insertion of a washer between said shoulder and felly, the bar being held in the meantime by the pawl, which sets in the ratchet on said bar. The bent bar T receives the direct downward strain against the hub, and prevents the head from being forced laterally, which would bend or break the spokes, the clamps serving to hold the device in place in connection with the bar. When the washer is properly secured, the pawl is released, and the felly springs back upon the washer, binding the parts of the wheel securely together.

Having thus described my invention, what I claim, and desire to secure by Letters Patent, is—

In a tire-tightener, the combination of the recessed head provided with a sliding bar having a lateral bifurcated extension adapted to straddle the spoke of a wheel, and provided with suitable cogs and ratchets, a cogged operating-lever, a stationary and hinged clamping-wing, and clamping devices, and an adjustable bent bar to rest upon the hub, the whole arranged to operate substantially in the manner specified.

In testimony whereof I affix my signature, in presence of two witnesses, this 27th day of February, 1883.

JAMES S. PURSLEY.

Witnesses:

R. N. PURSLEY,
FRANK F. TURNER.
